UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

MOLDING MACHINE.

Application filed May 10, 1926. Serial No. 108,012.

My invention relates, more particularly, to sand molding machines, and as to certain features thereof to such machines of a construction adapted to be shifted on the floor 5 along or over a pile of molding sand disposed thereon.

My object, generally stated, is to provide improvements in molding machines, to the end that the molding operation may be facilitated and perfect molds be made therefrom.

Certain of my more particular objects are to provide in a molding machine particularly of the type which is movable along the 15 floor and is equipped with means for jolting the sand in the flask, for preventing rebounding of the sand in the flask in the jolting operation and minimizing danger of breakage of the part against which the flask 20 support strikes in the jolting operation; to provide in a molding machine of the squeezer type, for the ready and accurate positioning of the flask upon its support to ensure proper registration of the flask with 25 the squeezer head and preferably to provide for the so centering of flasks of different sizes; to provide means readily accessible to the operator while at the machine, for receiving and supporting the cope portion of a 30 flask following the production of the mold; to provide a molding machine which shall be so constructed that it may be caused to straddle a pile of the molding sand and be 35 rollingly supported at opposite sides thereof to permit the machine to be moved along the pile, as desired, and be readily converted 40 into a machine of the non-straddling type; and to provide in a molding machine of the sand-squeezing type for the ready and convenient 45 vertical adjustment of the squeezer head, as desired, without requiring the use of a wrench.

Referring to the accompanying drawings:—

Figure 1 is a view in front elevation of a molding machine embodying my improvements. Figure 2 is a plan view thereof. Figure 3 is an enlarged section taken at the line 3—3 on Fig. 2 and viewed in the direction of the arrows. Figure 4 is a view in side elevation of the machine, the machine, according to this figure being viewed from the left-hand side of Fig. 1; and Figure 5, a plan sectional view taken at the line 5 on Fig. 1 and viewed in the direction of the

arrow, this view showing the details of the flask centering, or gaging, device.

Inasmuch as certain of the features of my invention relate to machines of the so-called sand-straddling type, I have chosen 60 to illustrate them in such a machine, the machine shown comprising a base portion 10 provided with depending spaced apart arms 11 in which one of the supporting wheels of the machine, and represented at 12, is rotatably mounted. Extending laterally from the member 10 is a bracket 13 in which a shaft 14 is mounted to extend at opposite sides of the body 10, the support for this shaft at its other end being represented at 15. The shaft 14 adjacent to, and beyond, the bracket 13 is provided with another of the wheels for supporting the machine and represented at 16. Extending laterally from the side of the base 10 opposite 70 that at which the wheel 16 is located, is an arch-shaped extension frame 17 which is detachably connected, by the screws 18, to the base 10 and is provided at its outer end with a shaft 19 on which still another supporting wheel for the machine and represented at 20, is journaled.

It may be here stated that in the use of the machine with the extension 17 thereon, the machine may be caused to be supported to straddle, at this extension, a pile of sand extending along the floor, and permit of the movement of the machine along the pile as the sand is removed therefrom in the operation of producing molds on the machine, 80 the extension frame 17 by reason of its detachable connection with the base 10 being disconnectable therefrom in which case the wheel 20 would be removed from the shaft 19 and mounted upon the end of the shaft 75 14 opposite that carrying the wheel 16 thereby permitting the machine to be moved along the side of a pile of sand, without straddling it.

The machine shown is adapted for both 100 the jolting of the flask to pack the sand therein, and the elevating of the flask thereafter into engagement with a squeezer-head to further compress the sand, and to this end comprises a piston device 21 extending 105 at its lower end into a cylinder 22 forming a squeezer-cylinder and shown as formed in the base member 10 in direct vertical alignment with the center of the supporting wheel 12. The piston device referred to 110

comprises the piston proper 23 which is screwed upon the lower end of a hollow jolt-cylinder 24 which extends upwardly beyond the cylinder 22 and is provided with an outwardly-extending annular peripheral flange 25 which extends directly above a ring member 26 screwed into the upper end of the cylinder 22 and in which the hollow cylinder 24 has sliding fit. The piston device also comprises a cylindrical piston-member 27 which extends through the central opening 28 in a ring 29 resting upon the top of the flange 25 and downwardly into the hollow cylinder 21, in which the member 27, which forms a jolt-piston, is reciprocable, the piston 27 being provided at its upper end with a jolt-table 30 bearing upon the ring 29. It may be here stated that the cylinder 24 has associated therewith, means for supplying compressed air thereto beneath the piston 27 and exhausting it therefrom, in rapid alternation, to effect the rise of the piston 27 together with the flask thereon, and thereafter permit this piston to drop against the ring 29 by rapid successive movements thereby producing the jolting operation. The cylinder 22 has associated therewith means for supplying compressed air thereto beneath the piston 23 to force the latter together with this flask thereon, upwardly into cooperating position relative to a squeezer-head hereinafter referred to, to perform the squeezing function. As mechanisms for selectively supplying compressed air to the cylinders 22 and 24 for the purposes above stated are well known in the molding machine art, detailed illustration and description thereof is omitted, it being understood that any suitable mechanisms for producing the operations stated may be provided.

As shown the depending arms 11 are spaced apart a comparatively short distance and extend within the vertical curved plane of the cylinder 22 for a purpose hereinafter set forth.

The machine also comprises a column 31 which is located to one side of the cylinder 22 and is rigidly secured in an opening 32 in the base 10, the upper end of this column being provided with the squeezer-head mechanism which cooperates with the piston device 21 to permit the squeezing operation. The squeezer device is represented generally at 33 it being shown as formed of a bracket 34 provided at one end with vertically spaced sleeve portions 35 and 36 which surround the column 31 about which this bracket is adapted to be swung on a vertical axis, the bracket being supported in fixed vertical position by a split clamping sleeve 37 located between the sleeve portions 35 and 36 and surrounding the column 31 and rigidly secured thereto, the sleeve 37 being provided with stop-lugs 38 and 38^a located in

different radial positions about the sleeve 37 and extending into the path of swinging movement of the bracket 33. The outer, free, end of the bracket 33 is equipped with the squeezer-head represented at 39, the various parts of the machine being so proportioned and arranged, as shown, that the squeezer-head 39 extends directly above, and in vertical alignment with, the center of the piston device 21 when the bracket 33 is swung into engagement with the stop 38 to the position shown in the drawings. The squeezer-head 39 is rigidly secured to the lower end of a screw-rod 40 which extends upwardly through a vertical non-threaded opening in the bracket 33, this rod having threaded thereon nuts 41 and 42 which are located, respectively, above and below the bracket 33; and by the adjustment of which relative to the rod 40, the height to which the squeezer-head 39 extends, may be regulated, the bracket 33 being provided with a yoke-shaped member 43 pivoted thereon at 44 and adapted, when in the position shown in Fig. 4, in which position it straddles and interlocks with the nut 41, to hold this nut against rotation.

The column 31 also carries means serving as a gage to permit of the accurate and ready centering of the flask on the flask-table 30, relative to the squeezer-head 39 so that when the flask, after being filled with sand, is elevated to engage the sand with the squeezer-head, the latter will freely enter the open end of the flask, to ensure the proper squeezing result. These gaging means, as shown, comprise a centrally-apertured block which surrounds the column 31 and to which it is rigidly secured in any desired position of vertical adjustment by a set-screw 45^a; a yoke-shaped plate 46, the arms 47 of which straddle the column 31 and fit flatwise against the block 45 to which latter the member 46 is connected, for in and out adjustment, by bolts 48 carried by the block 45 and extending through slots 49 in the arms 47; and a gage bar 50 which extends crosswise of the yoke 46 and to which it is secured by bolts 51 provided on the outer end of the plate 46 and extending through slots 52 in this bar and permitting of the adjustment of the latter in a direction crosswise of the plate 46, the outer end of the bar 50 being provided with a projection 53 disposed at a right angle to the body portion of the bar 50, the interior angle provided between this extension and the body of the bar 50 being adapted to receive a corner of a flask positioned on the table 30. The parts of these gaging means being adjustable relative to the axis of the column 31 in planes at right angles to each other, permits of the setting of the gage bar 50 in the proper position for correctly positioning the flask on the table 30 for accurate registration.

with the squeezer-head 39, it being understood that these gaging means would be provided at such an elevation, relative to the top 30, that a flask, positioned on this table, 5 will extend at its side portion into the angle provided by the bar 50.

As a means for supporting, at a point convenient to the operator of the machine, tools, flasks, patterns, and other articles which he 10 may require in the producing of the flasks, I provide at the side of the machine opposite that at which the extension frame 17 extends, a platform, or bench, 54 which is pivoted at one end on a shaft 55 extending laterally from a bracket 56 secured to the base 10, and is provided at its opposite end with a supporting leg 56^a, braced at 57, and equipped at its lower end with a wheel 58 adapted to bear upon the floor, the feature 15 of pivoting this bench adapting the latter to be swung out of engagement with the floor when it is desired to move the machine.

The machine is also provided with means for supporting the cope at a point convenient to the operator at the machine, these 20 means comprising a member presenting parallel vertically extending rod portions 59 which extend upwardly through openings in flanges of the bracket 33 and are located at 25 opposite sides of the vertical axis of the column, the upper ends of these rods carrying set-screw-equipped collars 60 which rest upon the top of the bracket 33 and hold the rods 59 in suspended position, the lower ends 30 of these rods terminating in a laterally extending yoke portion 61 shown as formed integrally with these rods at which portion a cope may be supported, this cope-rest being 35 so positioned relative to the bracket 33 that 40 when the latter is swung to a position in which the head 39 is out of vertical alignment with the flask-table the yoke 61 extends directly above this table.

Referring to the operation of the machine, 45 the operator places the pattern, which, by way of example, may be mounted on a sand-match or follow-board, on the table 30 and places the flask in position thereon. He then fills the sand into the flask, and then opens 50 the supply of compressed air to the cylinder 21 to effect the jarring of the piston mechanism and the flask thereon which operates to compact the sand in the flask. The excess sand is then struck off from the top of the 55 flask and the bottom board placed on the mold therein. The operator then moves the flask into a position to engage the gaging device above described to properly center the flask on the table 30, and then swings 60 the bracket 33 to the position shown in the drawings in which the squeezer-head 39 extends accurately centered relative to the flask. Compressed air is then supplied to the cylinder 22 to lift the piston 21 for forcing 65 the mold, at the bottom board thereon,

into engagement with the squeezer-head 39 to effect the proper compressing of the sand in the flask. After lowering the piston device 21 to the position shown in Fig. 3 by permitting the air to exhaust from the 70 cylinder 22, the operator swings the bracket 33 out of the position last referred to, inverts the flask and, where a sand-match is employed, as above suggested, then removes the match which leaves the pattern in the 75 molded sand in the drag-flask. The cope-portion of the flask is then placed on the drag and filled with sand and the drag again moved into engagement with the gaging means referred to, the bracket 33 swung back 80 to the position shown in the drawings and air again admitted to the cylinder 22 to lift the piston device 21 and squeeze the sand in the cope. The piston device 21 is again lowered and the bracket 33 again 85 swung out of the squeezing position, which carries the cope-rest 61 into a position in which it extends directly in front of the operator in position to receive the cope removed from the flask by the operator. After 90 drawing the pattern from the drag the cope is replaced on the latter to finish the mold.

It will be understood from the foregoing that by constructing the machine as shown and described it may be readily converted from one of the sand-straddling type to one of the non-straddling type, and vice versa, to adapt the machine to different conditions of use.

The feature of supporting the wheel 12 100 in closely spaced bearing members 11 provided directly below the cylinder 22 and preferably centrally thereof as shown is of importance as springing of the cylinder 22 with objectionable rebound and displacement 105 of the sand in the flask and likelihood of eventual crystallization and fracture, is prevented. Furthermore, by locating this wheel directly beneath the piston and cylinder mechanism which is the heaviest part of the machine, the machine may be turned around with ease in shifting it over the floor and within a circle of very short radius, as it may be readily tilted by hand into a position 110 in which it rests on the floor at its central and outermost wheels 12 and 20, respectively, only. The feature of providing the nut-holding member 43 is of advantage in the adjustment of the squeezer-head 115 39 on the bracket 33. By providing for the holding of the nut 43 stationary, the clamping effect of the nuts 41 and 42 may be relieved by rotating the screw-rod 40 in counterclockwise direction in Fig. 2 and the clamping effect produced by rotating this 120 rod in the other direction. With the clamping effect relieved, as stated, the operator may readily adjust the nut 42 on the rod 40, and the rod 40 on the nut 41, to cause 125 the head 39 to extend above or below a 130

given position, and then simply by rotating the rod 40, in counterclockwise direction in Fig. 2, automatically effect the clamping of the rod 40 to the bracket 33 by the engagement of the nuts 41 and 42 with the latter.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In a molding machine, the combination of a supporting structure having wheels by which it is adapted to be supported on a floor, and squeezing means on said structure comprising relatively movable members arranged one above the other, one of said supporting wheels being centralized relative to the longitudinal axis of the lower one of said members.
2. In a molding machine, the combination of a supporting structure, a sand-pile-straddling member detachably connected with said structure, a supporting wheel on the outer end of said member, wheels on said structure cooperating with the wheel on said member to support the machine, said structure having a journaling part for a wheel at the side thereof adjacent said member which latter wheel when in place on said journaling part, and said member is detached from said structure, cooperates with the wheels on said structure to support the machine.
3. In a molding machine, the combination of a flask-support, a standard arranged alongside of said support, a supporting member on said standard, a squeezer-head on said supporting member, said supporting member being swingable on said upright about a vertical axis into and out of a position in which said head extends directly above said support, said support and head being relatively movable toward each other to perform the squeezing operation, and a cope-rest extending laterally from said supporting member in such position that when said supporting member is swung to a position in which said head extends out of vertical alignment with said flask-support said cope-rest will extend from said supporting member toward said flask-support, said cope-rest being adjustable vertically to cause it to extend at different heights.
4. In a molding machine, the combination of a flask-support, a standard arranged alongside of said support, a supporting member on said standard, a squeezer-head on said supporting member, said supporting member being swingable on said upright about a vertical axis into and out of a position in which said head extends directly above said support, said support and head being relatively movable toward each other, and a gaging-device rotatably mounted on said upright to swing in a horizontal plane and engageable by the flask on said support for centering the flask relative to said squeezer-head.
5. In a molding machine, the combination of a flask-support, a standard arranged alongside of said support, a supporting member on said standard, a squeezer-head on said supporting member, said supporting member being swingable on said upright about a vertical axis into and out of a position in which said head extends directly above said support, said support and head being relatively movable toward each other to perform the squeezing operation, and a cope-rest extending laterally from said supporting member in such position that when said supporting member is swung to a position in which said head extends out of vertical alignment with said flask-support, said cope-rest will extend from said supporting member toward said flask-support, said cope-rest being in the form of a yoke extending laterally of said upright and having upwardly extending rod-portions at which said cope-rest is connected with said support.
6. In a molding machine, the combination of a frame, flask-supporting piston and cylinder mechanism on said frame, and supporting wheels on said frame, one of said wheels being so located that it bears more of the load imposed by said mechanism than is borne by any of the others of said wheels.
7. In a molding machine, the combination of a frame, flask-supporting piston and cylinder mechanism on said frame, and supporting wheels on said frame, one of said wheels being substantially centralized relative to the vertical axis of said mechanism.
8. In a molding machine, the combination of a frame, piston and cylinder jolt mechanism on said frame, wheels supporting said frame, and journaling supports for one of said wheels depending from the cylinder of said mechanism and located directly beneath said cylinder and between which said wheel is positioned.
9. In a molding machine, the combination of an upright, a flask support adjacent to, and located to one side of, said upright, a squeezer-head on said upright, said support and head being relatively movable toward each other, and a gaging-device rotatably mounted on said upright to swing in a horizontal plane and engageable by the flask on said support for centering the flask relative to said squeezer-head.
10. In a molding machine, the combination

being relatively movable toward each other to perform the squeezing operation, and a cope-rest extending laterally from said supporting member in such position that when said supporting member is swung to a position in which said head extends out of vertical alignment with said flask-support, said cope-rest will extend from said supporting member toward said flask-support, said cope-rest being in the form of a yoke extending laterally of said upright and having upwardly extending rod-portions at which said cope-rest is connected with said support.

5. In a molding machine, the combination of a flask-support, a standard arranged alongside of said support, a supporting member on said standard, a squeezer-head on said supporting member, said supporting member being swingable on said upright about a vertical axis into and out of a position in which said head extends directly above said support, said support and head being relatively movable toward each other to perform the squeezing operation, and a cope-rest extending laterally from said supporting member in such position that when said supporting member is swung to a position in which said head extends out of vertical alignment with said flask-support, said cope-rest will extend from said supporting member toward said flask-support, said cope-rest being adjustable vertically to cause it to extend at different heights.

6. In a molding machine, the combination of a frame, flask-supporting piston and cylinder mechanism on said frame, and supporting wheels on said frame, one of said wheels being so located that it bears more of the load imposed by said mechanism than is borne by any of the others of said wheels.

7. In a molding machine, the combination of a frame, flask-supporting piston and cylinder mechanism on said frame, and supporting wheels on said frame, one of said wheels being substantially centralized relative to the vertical axis of said mechanism.

8. In a molding machine, the combination of a frame, piston and cylinder jolt mechanism on said frame, wheels supporting said frame, and journaling supports for one of said wheels depending from the cylinder of said mechanism and located directly beneath said cylinder and between which said wheel is positioned.

9. In a molding machine, the combination of an upright, a flask support adjacent to, and located to one side of, said upright, a squeezer-head on said upright, said support and head being relatively movable toward each other, and a gaging-device rotatably mounted on said upright to swing in a horizontal plane and engageable by the flask on said support for centering the flask relative to said squeezer-head.

10. In a molding machine, the combination

- of an upright, a flask support adjacent to, and located to one side of, said upright, a squeezer-head on said upright, said support and head being relatively movable toward each other, and a gaging-device mounted for vertical adjustment on said upright and engageable by the flask on said support for centering the flask relative to said squeezer-head.
- 10 11. In a molding machine, the combination of an upright, a flask support adjacent to, and located to one side of, said upright, a squeezer-head on said upright, said support and head being relatively movable toward each other, and a gaging-device rotatably mounted on said upright to swing in a horizontal plane and adjustable vertically thereon and engageable by the flask on said support for centering the flask relative to said squeezer head.
- 15 12. In a molding machine, the combination of an upright, a flask support adjacent to, and located to one side of, said upright, a squeezer-head on said upright, said support and head being relatively movable toward each other, and a gaging device rotatably mounted on said upright to swing in a horizontal plane and presenting an interior angle for engagement by a corner of the flask on said support and operating to center the flask relative to said squeezer head.
- 20 13. In a molding machine, the combination of an upright, a flask support adjacent to, and located to one side of, said upright, a squeezer-head on said upright, said support and head being relatively movable toward each other, and a gaging-device rotatably mounted on said upright to swing
- in a horizontal plane and engageable by the flask on said support for centering the flask relative to said second squeezer head, said gaging-device being adjustable for engaging flasks of different sizes.
- 25 14. In a molding machine, the combination of an upright, a flask support adjacent to, and located to one side of, said upright, a squeezer-head on said upright, said support and head being relatively movable toward each other, and a gaging-device rotatably mounted on said upright to swing in a horizontal plane and engageable by the flask on said support for centering the flask relative to said squeezer head, said gaging device being formed of sections adjustable relative to each other in a plurality of directions.
- 30 15. In a molding machine, the combination of an upright, a flask support adjacent to, and located to one side of, said upright, a squeezer-head on said upright, said support and head being relatively movable toward each other, and a gaging-device rotatably mounted on said upright to swing in a horizontal plane and engageable by the flask on said support for centering the flask relative to said squeezer-head, said gaging-device being formed of sections at one of which it is supported on said upright and at which it is adjustable toward and away from said upright, the other of said sections being in the form of a bar adjustable on said first-referred-to section at an angle to the line of adjustment of the latter on said upright and presenting an interior angle portion to receive a corner of the flask on said upright.

HENRY TSCHERNING.
